(***) Term: **15 Years***Primary Examiner* — Paula Allen Greene(21) Appl. No.: **29/725,667***(74) Attorney, Agent, or Firm* — Polsinelli PC(22) Filed: **Feb. 26, 2020****CLAIM****Related U.S. Application Data**

I claim the ornamental design for a headphone, as shown and described.

(63) Continuation of application No. 29/672,594, filed on Dec. 6, 2018, now Pat. No. Des. 887,391.

DESCRIPTION(51) **LOC (13) Cl.** **14-01**

FIG. 1 is a perspective view of a first embodiment of a

(52) **U.S. Cl.**

headphone, showing my new design;

USPC .....

FIG. 2 is a front elevational view thereof;

(58) **Field of Classification Search**

FIG. 3 is a rear elevational view thereof;

USPC D14/205, 188, 192; D29/112; 2/209;
381/380, 381, 383, 370; 455/90.3, 575.1,
455/569.1

FIG. 4 is a left side elevational view thereof;

CPC H04R 25/00; H04R 25/02; H04R 1/1016;
H04R 1/1066; H04R 5/033; H04R
5/0335; H04R 1/105; H04R 1/1008;
H04R 1/1083; H04R 1/1091

FIG. 5 is a right side elevational view thereof;

See application file for complete search history.

FIG. 6 is a top plan view thereof; and

FIG. 7 is a bottom plan view thereof.

FIG. 8 is a perspective view showing the headphone in a

U.S. PATENT DOCUMENTS

folded position thereof;

3,053,944 A * 9/1962 Weeks H04R 1/1066

FIG. 9 is a front elevational view thereof;

381/377

FIG. 10 is a rear elevational view thereof;

3,815,155 A 6/1974 Davison et al.

FIG. 11 is a left side elevational thereof;

D235,210 S 5/1975 Hill

FIG. 12 is a right side elevational view thereof;

4,471,496 A 9/1984 Gardner, Jr. et al.

FIG. 13 is a top plan view thereof; and,

D292,205 S 10/1987 Kikutani

FIG. 14 is a bottom plan view thereof.

4,905,322 A 3/1990 Aileo et al.

The dash-dot broken lines immediately adjacent the shaded

areas encompassing unshaded regions, represent the bounds

of the claimed design while all other broken lines are

directed to environment and are for illustrative purposes

only and form no part of the claimed design.
